DESIGN FOR A TEXTILE FABRIC OR SIMILAR ARTICLE OF MANUFACTURE

William E. Reynolds, Glen Rock, N. J., and Raymond Harvey, New York, N. Y.

Application June 26, 1934, Serial No. 52,346

Term of patent 14 years

To all whom it may concern:

Be it known that we, WILLIAM E. REYNOLDS, a citizen of the United States of America, residing at Glen Rock, in the county of Bergen and State of New Jersey, and RAYMOND HARVEY, a subject of the King of Great Britain, residing in the Borough of Manhattan, city, county, and State of New York, have invented a new, original, and ornamental Design for a Textile Fabric or Similar Article of Manufacture, of which the following is a specification, reference being had to the accompanying drawing, forming a part thereof, and showing a face view of a piece of textile fabric embodying our design.

The design is intended to be repeated on the textile fabric as shown.

We claim:

The ornamental design for a textile fabric or similar article of manufacture substantially as shown and described.

WILLIAM E. REYNOLDS.
RAYMOND HARVEY.
